[57] CLAIM

The ornamental design for a scraper to remove food from a plate, as shown and described.

DESCRIPTION

FIG. 1 is a front top perspective view of the scraper to remove food from a plate of the present invention showing my new design with the phantom lines depicting solely environmental structure and forming no portion of the claimed design;

FIG. 2 is an enlarged front top perspective view thereof;

FIG. 3 is a side elevational view thereof;

FIG. 4 is a top plan view thereof; and,

FIG. 5 is a rear elevational view thereof.
